(57) **CLAIM**

The ornamental design for a rearview mirror for truck, as shown and described.

DESCRIPTION

FIG. 1 is an isometric view of the rearview mirror as seen from one side and the front;

FIG. 2 is a front elevation view of the rearview mirror;

FIG. 3 is a rear elevation view of the rearview mirror;

FIG. 4 is a side elevation view of the rearview mirror as seen from the right of FIG. 2;

FIG. 5 is a side elevation view of the rearview mirror as seen from the left of FIG. 2;

FIG. 6 is a top elevation view of the rearview mirror, the bottom being a mirror image; and,

FIG. 7 is an isometric view of one of the five wishbone-shaped elements shown in FIGS. 1 and 2.
